UNITED STATES PATENT OFFICE

101,453

DESIGN FOR A TEACUP OR SIMILAR ARTICLE

Stella I. Gunther, Chicago, Ill.

Application July 27, 1936, Serial No. 64,091

Term of patent 14 years

To all whom it may concern:

Be it known that I, Stella I. Gunther, a citizen of the United States, residing at Chicago, in the county of Cook and State of Illinois, have invented a new, original, and ornamental Design for a Teacup or Similar Article, of which the following is a specification, reference being had to the accompanying drawing, forming a part thereof.

In the drawing,

Fig. 2 is a side elevation thereof.

I claim:

The ornamental design for a teacup or similar article, substantially as shown.

STELLA I. GUNTHER.
